UNITED STATES PATENT OFFICE.

THOMAS MADDOCK, OF NEW YORK, N. Y., ASSIGNOR TO HENRY MADDOCK,
OF SAME PLACE.

DESIGN FOR TABLE-WARE.

SPECIFICATION forming part of Design No. 16,572, dated March 16, 1886.

Application filed January 30, 1886. Serial No. 190,373. Term of patent 7 years.

To all whom it may concern:

Be it known that I, THOMAS MADDOCK, a subject of the Queen of Great Britain, and a resident of the city, county, and State of New York, have invented or produced a new and original Design for Table-Ware, of which the following is a specification, reference being had to the accompanying drawings, forming part thereof.

10 Figure 1 is a side elevation of one piece of the ware embodying my design. Fig. 2 is a plan of the same. Fig. 3 is an end elevation of the same.

The leading features of my design consist in 15 the peculiar contour of the body, which is in the form of an inverted frustum of an eight-sided pyramid, the sides of which are planes, and in the peculiar contour of the cover, which is also in the form of a frustum of an 20 eight-sided pyramid with plane sides.

The details of the design will be set forth hereinafter.

The piece of table-ware shown in the drawings is a dish, of which A is the body, provided with like handles, A' A', at its ends, and B is the removable cover, provided with a handle, B', of substantially the same design 25 as the handles A'.

The leading characteristic of the design of 30 the body A is its shape or contour. The body has the form of an inverted frustum of an eight-sided pyramid having two equal wide faces, a a, two equal narrower faces, b b, and four equal still narrower faces, c c, at the corners of the dish. These faces, which are all planes, all extend down to the base-line, d, of the dish, without a break or curve in the contour-lines, there being no "foot," properly so called, on the dish.

40 a', b', and c' represent faces at the upper margin of the dish-body, corresponding with the several faces a, b, and c, respectively. These faces a', b', and c' project out a little beyond the planes of the several faces a, b, and 45 c, and there is a slight shoulder on the horizontal line e.

The design of the upper edge of the body A presents a scalloped appearance, f f representing the scallops.

50 The handles A' are alike.

The design of the handle comprises the representation of two rolled-up leaves, g g, at the ends of the handle where they join the body,

and the representation of a bar, h, between the leaves, which has four facets or faces, i i, 55 on its outer or upper side.

The handles stand out at an angle of about forty-five degrees with the base of the body.

The design of the cover B is intended to harmonize with that of the body A. The base 60 portion of the cover has the shape or contour of a frustum of an eight-sided pyramid, the sides of which are planes, lettered j j, k k, and l l. On the top of this frustum is a raised table-like ornament, m, the scalloped contour-line n of which falls within the contour-line of the top of the frustum, as seen in Fig. 2. In the center of the ornament m is a raised table-like ornament, o, of the oblong form and contour shown in the drawings.

70 The handle B' on the cover is of the same design as the handle on the body, and its position with respect to the cover is clearly shown in the drawings.

I claim—

1. The design for table-ware herein shown and described, the same consisting of the design of the body A, which has the form of an inverted frustum of a pyramid with eight plane faces, which extend down to the bottom line, d, as described.

2. The design for table-ware herein shown and described, the same consisting of the design of the body A, which has the form of an inverted frustum of a pyramid with eight plane faces, a a, b b, and c c, at its lower part, eight corresponding faces, a' a', b' b', and c' c', at its upper part, which latter faces project beyond the former, and a scalloped upper edge, as described.

90 3. The design for table-ware herein shown and described, the same consisting of the design of the cover B, which has the form of the frustum of a pyramid with eight plane faces or sides, j j, k k, and l l, surmounted by a table-like ornament, m, which ornament is surmounted by a table-like ornament, o, as described.

95 In witness whereof I have hereunto signed my name in the presence of two subscribing witnesses.

100 THOMAS MADDOCK.

Witnesses:

HENRY CONNETT,
GEO. BANTON.
